UNITED STATES PATENT OFFICE

2,457,810

SEALING DEVICE FOR DRY CELLS

Grenville B. Ellis, Red Bank, N. J., assignor to the
United States of America as represented by the
Secretary of War

Application May 10, 1945, Serial No. 592,952

4 Claims. (Cl. 136—133)

(Granted under the act of March 3, 1883, as
amended April 30, 1928; 370 O. G. 757)

1

The invention described herein may be manufactured and used by or for the Government for governmental purposes, without the payment to me of any royalty thereon.

My invention relates to primary cells and more particularly to sealing means for said cells.

An object of my invention is to provide improved sealing means for a cell of the metal oxide-zinc type.

Another object of my invention is to provide a metal disc adapted so as to compressibly seal itself with a grommet of resilient material.

Another object of my invention is to provide a grommet of resilient material adapted so as to form a compressible seal between a metal disc and the free edge and shoulder of a cell container.

Another object of my invention is to provide a metal disc adapted so as to form the negative terminal of a cell.

A still further object of my invention is to provide a metal disc adapted so as to make an electric contact with the anode of a cell.

A primary cell is known in the art comprising an anode in the form of a strip of corrugated zinc foil contained within a roll of alkali-resistant material, a depolarizer cathode of reducible mercuric oxide, an electrolyte comprising a solution of potassium hydroxide saturated with zinc oxide, said electrolyte being held absorbed within said roll of alkali-resistant absorbent material, a container for said cell parts of iron or steel, said container being in contact with said depolarizer cathode of reducible mercuric oxide so as to form the positive terminal of said cell, and a zinc top for said container which forms the cover and the negative terminal of said cell, said zinc top being fitted into an elastic "Neoprene" ring or grommet, said zinc top and "Neoprene" ring assembly resting on the shoulder formed in the container wall, the free edge of the container being spun firmly down over the top edge of the grommet. The mentioned cathode is disposed at the bottom of the container, with the anode above it, the two electrodes being separated by a porous disc.

The herein above described cell under test was observed to have a tendency to leak or to have a certain amount of creepage of the potassium hydroxide electrolyte. My invention will eliminate said leakage and prevent the creepage of the potassium hydroxide electrolyte.

My invention will be more fully understood from the following detailed description taken in connection with the accompanying drawing, wherein I have shown a preferred embodiment thereof.

2

Referring to the drawing:

Fig. 1 is a sectional perspective view of the metal disc,

Fig. 2 is a sectional perspective view of the grommet, and

Fig. 3 is a sectional view of the cell assembly.

Referring to Fig. 1, my device consists of a metal disc 10, such as a zinc disc, with a downwardly extending skirt 11. The grommet 12 in

Fig. 2 is inwardly beveled at 13 and 14. The metal disc 10 of Fig. 1 fits closely in the circular channel 15 of the grommet 12 and the downwardly extending skirt 11 of Fig. 1 fits closely through the circular opening 16 of grommet 12. Refer-

ring to Fig. 3, the metal disc 10 is shown in the assembled position with the downwardly extending skirt 11 peened outwardly, and also upwardly against the lower portion of the grommet. Thus,

a channel is formed in the disc, into which channel the inner part of the lower portion of the grommet is sealed. The disc and the grommet are thus both channeled, with the channels ex-

tending in opposite directions, so that a part of each of these coacting members is sealed into the channel of the other, which construction pro-

vides a very effective double seal. The metal disc-grommet assembly 17 rests compressibly upon the shoulder 18 of the container 19. The

peened portion of the downwardly extending skirt 11 of the metal disc 10 makes close electric contact with anode 20. The free edge 21 of the

container 19 is spun firmly down over the top edge 22 of grommet 12 for the purpose of perma-

nently pressing the disc 10 against the anode 20.

Having thus described my invention I desire to secure by Letters Patent and claim:

1. In a primary cell comprising a metallic container, electrodes and an electrolyte within the container, the combination of a metallic disc on one of the electrodes, a grommet insulating the disc from the container, said disc and grommet having opposed annular interfitting channels each sealingly receiving a portion of the other.

2. In a primary cell comprising a metallic container, electrodes and an electrolyte within the container, the combination of a metallic disc on one of the electrodes, a resilient grommet insulating the disc from the container, said disc and grommet having opposed annular interfitting channels each sealingly receiving a portion of the other, the upper marginal portion of the container being pressed inwardly and downwardly onto the grommet.

3. In a primary cell comprising a metallic container, electrodes and an electrolyte within the

container, the combination of a metallic disc on one of the electrodes, a resilient grommet insulating the disc from the container, said disc and grommet having opposed annular interfitting channels each sealingly receiving a portion of the other.

4. In a primary cell comprising a metallic container, electrodes and an electrolyte within the container, the combination of a metallic disc on one of the electrodes, a grommet insulating the disc from the container, said disc and grommet having opposed annular interfitting channels each sealingly receiving a portion of the other, the container having a shoulder on which the disc-grommet combination is supported.

15 GRENVILLE B. ELLIS.
